ATTORNEY

UNITED STATES PATENT OFFICE

127,594

DESIGN FOR A HAND CARRIED TRAFFIC SIGNAL

Gladys Stewart, Oakland, Calif.

Application February 1, 1941, Serial No. 98,656

Term of patent 14 years

To all whom it may concern:

Be it known that I, Gladys Stewart, a citizen of the United States, residing in the city of Oakland, county of Alameda, State of California, have invented a new, original, and ornamental Design for a Hand Carried Traffic Signal, of which the following is a specification, reference being had to the accompanying drawing, forming part thereof.

Fig. 1 is a plan view of the hand carried traffic signal, showing my new design.

Fig. 2 is a side elevation of the same.

I claim:

The ornamental design for a hand carried traffic signal, as shown.

GLADYS STEWART.
